UNITED STATES PATENT OFFICE.

WALTER S. POLLARD, OF PHILADELPHIA, PENNSYLVANIA.

SWIMMING POOL.

Application filed January 8, 1924. Serial No. 684,920.

To all whom it may concern:

Be it known that I, WALTER S. POLLARD, a citizen of the United States, and a resident of the city of Philadelphia, county of Philadelphia, State of Pennsylvania, have invented a new and useful Swimming Pool, of which the following is a specification.

My present invention comprehends a novel construction and arrangement of a swimming pool, whereby the purification of the water is provided for and whereby the material collecting on the surface of the water is removed.

It further comprehends a novel construction of a swimming pool provided with visible and invisible skim outlets which communicate with a discharge conduit leading to a filtration system and wherein provision is made for returning the filtered water to the pool in such a manner as to aerate it before it enters the pool.

Other novel features of construction and advantages will hereinafter more clearly appear in the detailed description and the appended claims.

For the purpose of illustrating the invention, I have shown in the accompanying drawing a typical embodiment of it, which, in practice, will give reliable and satisfactory results. It is however to be understood that this embodiment is typical only and that the various instrumentalities of which my invention consists can be variously arranged and organized, and that the invention is not limited to the precise arrangement and organization of these instrumentalities as herein set forth.

Figure 1 represents a top plan view of a swimming pool.

Figure 2 represents a section taken substantially on line 2—2 of Figure 1.

Similar numerals of reference indicate corresponding parts.

Referring to the drawings:

45 1 designates a swimming pool embodying my invention. The swimming pool is provided with a surrounding wall 2, which in practice is ordinarily constructed of concrete, reinforced if desired. Contained 50 within the wall is a drain 3 which leads to a desired point of discharge. Beneath the top surface of the wall on one or more sides, I provide a step 4 from which leads the ports 5 of the visible skim outlets which 55 communicate with the drain 3. These visible skim outlets are formed between the

walls or treads 6, which are preferably semi-circular in outline. One wall of the swimming pool is provided with invisible skim outlets 7 which communicate with the drain 3, and the walls leading to such outlets preferably converge towards the drain, as indicated at 8. The main 3 is provided with a desired number of settling chambers 9 which are filled with sand as indicated at 10. The bottom 11 of the swimming pool is preferably formed of reinforced concrete and has the elongated ports 12 which communicate with the bottom mains 13, which communicate with the conduit 14 which 15 leads to a filter 15 of any desired or conventional type. The filtered water is forced from the filter 15 by means of a pump 16 through the conduit 17 to one or more stand pipes 18, which, if desired, may extend upwardly through a central support 19 preferably formed of reinforced concrete and provided with the steps 20 which extend above and below the surface of the water in the swimming pool. Each stand pipe 18 discharges at its upper end into a water container 21 from which leads a slide 22 which curves downwardly and is supported in proximity to its lower end by means of a support 23 of any desired character. The 25 water containers 21 form a tower having a platform 24, and a ladder 25 is provided to provide access to such platform.

Water aerating pipes 26 lead from the water containers 21, and are provided with 30 apertures 27 through which the water will spray with a fountain effect to effect the aeration of the water. The top of the tower is provided with any desired type of railing 28. In the operation of the swimming pool, 35 any matter which collects on the surface of the water will pass through the visible skim outlets 5 and the invisible skim outlets 7 into the drain 3 which in practice will preferably lead to the filter, but which, if desired, may discharge into the sewer.

The water withdrawn from the swimming pool through the filter 15 is filtered, and then forced by means of the pump 16 through the conduit 17 and the stand pipes 18 to maintain a continuous source of supply in the water containers 21. This water continuously flows in a thin stream down the bottom of the slides 22 and discharges into the water in the swimming pool. The water 105 from the containers 21 also discharge from the container 21 through the aerating pipes 110

26. The bottom of these pipes are preferably closed, so that the water issues from the discharge apertures of these pipes in the form of a spray which may fall into the 5 slides, or, if desired, directly into the water in the swimming pool.

The water flowing down the water slide causes a surface action on the pool towards its sides so that the surface water containing 10 the foreign material passes through the skimming ports into the drain contained within the walls of the pool, and therefrom to the filters.

The passages leading from the pool to the 15 skimming ports decrease in width towards such ports so that the proper skimming action is obtained to effect the removal of any foreign material floating on the water or contained in its top layer without any undue 20 waste of water or without materially increasing the cost of operating the pumping mechanism. The invisible outlets give a better appearance to the pool.

The aerating pipes have their discharge 25 ports arranged in any desired manner, and the discharge through these ports may take place on the slides or directly into the pool, as may be desired.

In accordance with my present invention, 30 the pool can be maintained in a sanitary condition and the water can be properly purified by aeration.

It will now be apparent that I have devised 35 a new and useful swimming pool which embodies the features of advantage enumerated as desirable in the statement of the

invention and the above description, and while I have, in the present instance, shown and described a preferred embodiment thereof of which will give in practice satisfactory 40 and reliable results, it is to be understood that this embodiment is susceptible of modification in various particulars without departing from the spirit or scope of the invention or sacrificing any of its advantages. 45

Having thus described my invention, what I claim as new and desire to secure by Letters Patent, is:

1. A swimming pool having a surrounding wall provided with laterally extending 50 visible and invisible skim outlets which decrease in width in the direction of the flow, and a drain communicating with said outlets.

2. A swimming pool having a surrounding wall the top surface of which forms a walk and provided with laterally extending 55 visible and invisible skim outlets disposed beneath said top surface which decrease in width in the direction of their lateral flow, and a drain in communication with said outlets.

3. A swimming pool having an offset wall provided with skimming ports, and curved laterally extending passages leading from 60 the pool to said ports.

4. A swimming pool having a wall provided with skimming ports, and with passages extending laterally discharging through said ports, said passages being 65 wider at their inlet portions than at their discharge portions.

WALTER S. POLLARD.
